United States Patent

Des. 239,503
Patented Apr. 13, 1976

239,503

GUTTER ACCESSORY

Boynton C. Hagaman, 6520 Elmhurst Drive,
Falls Church, Va. 22043

Filed Oct. 18, 1973, Ser. No. 407,560

Term of patent 14 years

Int. Cl. D8—08

U.S. Cl. D8—251

FIG. 1 is a perspective view of a gutter accessory showing my design;

FIG. 2 is a side view of an alternate embodiment;

FIG. 3 is a side view of another alternate embodiment; and

FIG. 4 is a bottom view of the gutter accessories of FIGS. 1-3.

I claim:

The ornamental design for a gutter accessory, as shown and described.
